[57] CLAIM

The ornamental design for self-adjusting tongs, substantially as shown and described.

DESCRIPTION

FIG. 1 is a perspective view of self-adjusting tongs showing my new design in a partially open position; FIG. 2 is a top plan view showing the tongs in closed position, the bottom plan view being identical; FIG. 3 is a front elevation view thereof; the rear elevation view being a mirror image; FIG. 4 is a right side elevation view thereof; and FIG. 5 is a left side elevation view thereof.

FIG. 1

FIG. 2

FIG. 3
